F. H. JENSEN.
ARCH SUPPORT.
FILED JUNE 24, 1921.

UNITED STATES PATENT OFFICE.

FRANK H. JENSEN, OF CHELSEA, MASSACHUSETTS.

ARCH SUPPORT.

Application filed June 24, 1921. Serial No. 480,025.

To all whom it may concern:

Be it known that I, FRANK HARRIS JENSEN, a citizen of the United States, residing at Chelsea, in the county of Suffolk, State 5 of Massachusetts, have invented a new and useful Arch Support; and I do hereby declare the following to be a full, clear, and exact description of the invention, such as will enable others skilled in the art to which 10 it appertains to make and use the same.

The invention relates to arch supporters and has for its object to provide a device of this character comprising an elongated elastic member having a foot engaging cuff 15 adapted to engage over the foot in registration with the arch, said cup being provided with a pocket for detachably holding a pad. Also to provide an extension to said elastic member which extension is adapted to be 20 passed upwardly over the foot and around the ankle and have its ends detachably connected to said extension, said extension forming means for exerting an upward pull on the cuff for maintaining the arch in 25 raised position.

With the above and other objects in view the invention resides in the combination and arrangement of parts as hereinafter set forth, shown in the drawings described and 30 claimed, it being understood that changes in the precise embodiment of the invention may be made within the scope of what is claimed without departing from the spirit of the invention.

35 In the drawings:—

Figure 1 is a perspective view of the arch supporter showing the same in position on a foot.

Figure 2 is a perspective view of the arch 40 supporter.

Figure 3 is a perspective view of one of the pads.

Referring to the drawings, the numeral 1 designates an annular member adapted to 45 encircle the foot 2 in registration with the arch 3 thereof, said annular member being preferably formed from elastic material so that the same will exert a contractable force on the foot adjacent the transverse arch. The 50 annular member 1 on its under face is provided with a pocket 4, in which pocket a wedge shaped pad 5 is disposed, said pad assisting in holding the arch in raised position.

55 Secured to the annular member 1 at 6 is an elongated elastic member 7, which mem-

ber is adapted to be stretched and passed around the ankle 8 and then downwardly and have its free end 9 attached to the main body of the member 7 by means of hooks 10 and eyes 11. It will be seen that with the body member 7 stretched and so attached that an upward pull will be exerted on the inner side of the annular cuff 1, thereby assisting in holding in raised position the 65 transverse arches of the foot. The material from which the annular member 1 and the elongated member 7 are formed may be of any material but preferably of the type wherein rubber strands are interwoven in a 70 piece of fabric.

From the above it will be seen that an arch supporter is provided which is simple in construction, easily applied to the foot and so constructed that it will be forced 75 upwardly by the ankle engaging extension thereby raising the inner side of the transverse arches.

The invention having been set forth what is claimed as new and useful is:—

1. An arch support comprising a flexible band for encircling a person's instep, a length of flexible material stitched to said band to form therewith a tapering pocket open both at its larger end and its smaller 85 end, and a tapering felt pad made of a length to project from both ends of the pocket, the projecting larger end permitting the easy grasping and withdrawal of the pad, and the projecting smaller end forming 90 by its lateral expansion under the compression incident to wear, shoulders for preventing the pad from working out from the pocket.

2. An arch supporter comprising a flexible 95 elastic band for encircling a person's foot, having a pocket beneath it, a yielding pad within said pocket, and a flexible elastic band permanently attached at one side of and close to the bottom of the first-named 100 band, and attaching devices for detachably fastening the other end of the second-named band to points near its attachment to the first-named band whereby a pull is given by the second-named band to the first-named 105 band tending to rotate the latter on the wearer's foot.

3. An arch support comprising a flexible elastic band for encircling a person's foot, having a yielding pad secured to its lowermost portion, a flexible elastic band attached at one end to a side of the first-named 110

band to pull the letter from a point close beside the hollow of the arch of the wearer, a plurality of eyes attached in a row extending longitudinally of the second-named band 5 and to the same near its attached end, and a corresponding row of hooks attached to the free end of the second-named band but transversely thereto.

In testimony whereof I have signed my name to this specification in the presence of 10 two subscribing witnesses.

FRANK H. JENSEN.
